Primary Examiner—Wallace R. Burke*Assistant Examiner*—Joel Sincavage*Attorney, Agent, or Firm*—Hovey, Williams, Timmons & Collins[57] **CLAIM**

The ornamental design for a holder for securing connection of electrical extention cords, as shown and described.

DESCRIPTION

FIG. 1 is a top plan view of a holder for securing connection of electrical extension cords showing my new design. The broken line showing of the electrical cord is included for the purpose of illustrating environmental elements only and forms no part of the claimed design; FIG. 2 is a front elevational view thereof, the rear elevational view thereof being a mirror image; FIG. 3 is a left side elevational view thereof, the right side elevational view thereof being a mirror image; and, FIG. 4 is a perspective view thereof as seen from the front and upper left.

FIG.1

FIG.2

FIG.3

U.S. Patent
